UNITED STATES PATENT OFFICE.

SHICKRALLA CONSTANTINE, OF NEW BEDFORD, MASSACHUSETTS.

WINDOW-SHADE AND CURTAIN-ROD HOLDER.

Application filed November 16, 1925. Serial No. 69,474.

This invention relates to a combined shade and curtain support and more particularly to a support which may be adjusted to meet the requirements of various widths of window frames and shades and curtains therefor.

It is an object of this invention to provide a combined shade and curtain supporting rod which can be clamped to a window frame without nails, screws or other fastening devices which mar the frame.

It is a further object of this invention to provide supports for the shade and curtain, each of which may be adjusted with respect to the supporting rod.

Other objects will be apparent from the following description taken in connection with the drawings, in which:

Figure 1 is a front elevation of the assembled shade and curtain support;

Figure 2 is a top plan view of the end clamp and curtain rod support;

Figure 3 is a sectional view taken on the line 3—3 of Figure 1;

Figure 4 is a perspective view of the shade holder; and

Figure 5 is a perspective view of the curtain rod support and clamp.

Referring to the drawings the rod 10 is threaded at one end and is provided at its other end with a shouldered wing nut 11. A tubular member 12, having an interior diameter slightly larger than that of the rod 10, is adapted to fit loosely on the rod so that the rod may be rotated with respect to the member 12. A second tubular member 13, similar to the member 12, has a slightly reduced interior diameter at one end, the reduced portion being threaded to permit the rod 10 to be secured into the tube 13.

To each of the tubular members 12 and 13, at the outer ends thereof, is secured in any suitable manner, such as by brazing, a combined window frame clamp and curtain rod support 14. This clamping member is preferably formed from a single L-shaped piece of metal and is provided with a right angularly bent tongue 15. Extensions 16 are bent about the opposite edges of the vertical arm to form a channel 17, as shown in Figure 3.

Adapted to slide within each of the channels 17 is a curtain rod support 18. As shown in Figure 2, the curtain rod support is clamped in the channel by means of

blocks 19 having threaded studs 20 which pass thru apertures in the support 18 and are drawn against the extension 16 by the thumb nuts 21. Vertical adjustment of the supports 18 may be made by loosening the nuts 21 and sliding the blocks in the channel until the desired position is obtained. The nuts are then tightened and the support is firmly clamped in the channel. 65 Each of the shade roller brackets 22 is preferably formed from a single piece of sheet metal. Near one end the blank is slit inwardly from each side and the portion adjacent the end is rolled and overlapped to 70 form a tubular section 23 of such diameter that it may be slipped over the tubular member 12 or 13. At a suitable point the section 23 is tapped to accommodate a set screw 24 for clamping the bracket on the 75 tubular member. The intermediate section of the bracket is partly curved to rest against the member 12 or 13 and is provided with wing extensions 25, the faces of which are substantially tangent to the tubular rod. When the assembled support is in position on a window frame the wings 25 bear against the frame and prevent rotation of the bracket about the rod 10. At the other end, the bracket 22 is bent at a right angle and provided with a slot 26 or aperture 27 into which the studs on the shade roller are placed.

The manner of applying the rod to a window frame will be readily understood by reference to Figure 1. The rod 10 is first screwed into the tubular member 13 until the length of the support is approximately equal to the width of the window. The support is then raised to the desired height and the wing nut turned until the right angular extensions 15 press tightly against the sides of the window frame. A clamping action is thus obtained and the assembled support will be held in position entirely by friction. 100 The curtain rod supports are then adjusted to the desired height, after which the curtain rods can be secured to their supports in the well known manner. Horizontal adjustment of the shade roller brackets is made by loosening the set screws 24 and sliding the brackets along the tubes 12 and 13 until the brackets are separated a distance equal to the length of the shade roller.

With the above described construction it 110 is apparent that the combined shade and curtain support may be secured to a window

frame at any desired height and easily removed therefrom without marring the window frame, the manner of fastening the support to the frame depending entirely on friction. The adjustability of the various parts permits application of the support to windows of different widths and enables one to place the several attachments in symmetrical relation to each other.

10 Altho the invention has been described in detail it is obvious that it may be modified within the scope of the appended claims.

Having thus described the invention, what is claimed as new and desired to be secured 15 by Letters Patent is:

1. A curtain support including two tubular members, unitary clamp and curtain rod supporting means on each of said members, said means including a rearwardly extending 20 clamp portion and an upwardly extending curtain rod support carrying portion, and a threaded rod to draw said clamps toward each other to secure said support to a window casing.

25 2. A curtain support including two tubular members, unitary clamp and curtain rod supporting means on each of said members, said means including a rearwardly extending clamp portion and an upwardly extending curtain rod support carrying portion, said support carrying portion formed as a 30 channel partly closed by overhanging projections, a curtain rod holder adjustable vertically along said channel, and a threaded

rod to draw said clamps toward each other 35 to secure said support to a window casing.

3. A curtain support including two tubular members, unitary clamp and curtain rod supporting means on each of said members, said means including a rearwardly extending 40 clamp portion and an upwardly extending curtain rod support carrying portion, a shade roller bracket mounted on each of said members, said bracket being adjustable independently of said curtain rod supporting means, and a threaded rod to draw 45 said clamps toward each other to secure said support to a window casing.

4. A curtain support including two tubular members, unitary clamp and curtain rod 50 supporting means on each of said members, said means including a rearwardly extending clamp portion and an upwardly extending curtain rod support carrying portion, said support carrying portion formed as a 55 channel partly closed by overhanging projections, a curtain rod holder adjustable vertically along said channel, a shade roller bracket mounted on each of said members, said bracket being adjustable independently 60 of said curtain rod supporting means, and a threaded rod to draw said clamps toward each other to secure said support to a window casing.

In testimony whereof I hereunto affix my 65 signature:

SHICKRALLA CONSTANTINE.
